UNITED STATES PATENT OFFICE.

ALLEN A. TIRRILL, OF PITTSBURGH, PENNSYLVANIA, ASSIGNOR TO WESTINGHOUSE ELECTRIC & MANUFACTURING COMPANY, A CORPORATION OF PENNSYLVANIA.

REGULATOR.

1,289,309.

Specification of Letters Patent. Patented Dec. 31, 1918.

Application filed September 9, 1916. Serial No. 119,274.

To all whom it may concern:

Be it known that I, ALLEN A. TIRRILL, a citizen of the United States, and a resident of Pittsburgh, in the county of Allegheny and State of Pennsylvania, have invented a new and useful Improvement in Regulators, of which the following is a specification.

My invention relates to electrical regulators of the vibratory-contact type, and it has special reference to the structural features of such regulators whereby their reliability of operation is improved.

The object of my invention is to provide a regulator that shall be positive and accurate in operation and devoid of all inherent mechanical vibrations which may prevent the main contact members from making firm and positive electrical contact with each other.

20 My invention is illustrated in the accompanying drawing, Figure 1 of which is a front view of a portion of a regulator embodying a form of my invention, and Fig. 2 is a side view showing in detail the mechanical connection between the plunger of the vibrating electromagnet and the lever controlling the movement of the movable main contact member of the regulator.

The regulator comprises a cast metal base 30 1 that is provided on its front face with a bracket 2 upon which is pivotally mounted at 3 a bell-crank lever 4. One arm of the lever 4 is substantially horizontal and the other is substantially vertical, the latter being bifurcated at its lower end to provide a pivot at 5 for a second lever 6. A right-angle bracket 7 is secured to the lever 6 adjacent to the pivot 5 and provides a mounting for a movable contact member 8 which 35 constitutes one of the main contact members of the regulator. A second contact member 9, resiliently mounted upon a spring element 10 and a bracket 11 extending from the base plate 1, coöperatively engages with 40 the movable contact member 8.

45 Engagement and disengagement between the two contact members is effected by means of two alternating current electromagnets 12 and 13 the former being known as the main control magnet and the latter as the vibrating magnet. The electromagnet 12 influences a core member 14 which is attached by means of a rod 14^a to one end of the lever 6. A slotted member 15 incloses 50 a projecting end 16 of the lever 6 for limit-

ing the rocking movement of the lever. A dash pot 17 retards the movement of the plunger 14. A counter-weight 18 is suspended by means of a spring element 19 from the other end of the lever 6.

60 The electromagnet 13 which is continuously subjected to increasing and decreasing excitations, in a well known manner which is common in all forms of regulators of this type, influences a plunger 20 that is connected by means of a stem 21 and a mechanism 22 to the horizontal arm of the bell-crank lever 4. A dash pot 23 retards the movement of the plunger 20. A counter-weight 24 suspended by a non-extensible element 25 is also 65 attached to the extremity of the horizontal arm of the bell-crank lever 4. The regulator shown in Fig. 1 is fully and completely described in my copending application Serial 70 No. 119,870, filed Sept. 13, 1916.

75 The present invention relates to the mechanism 22 which is interposed between the plunger 20 of the vibrating electromagnet 13 and the levers controlling the engagement and disengagement of the main contact members 8 and 9 of the regulator. With the stem 21 extending directly between the plunger 20 and the lever 4, as in regulators heretofore constructed, a very pronounced vibration was transmitted to the lever 4 by 80 reason of the alternating current impulses imparted by the electromagnet 13. At the same time, a buzz was produced at the pin 85 pivotally connecting the stem 21 to the lever. This vibration and buzz was especially noticeable when the regulator was subjected to normal excitation since the core 20 substantially floated, by reason of the balancing action between the core and counter-weights. 90 This vibration decreased the firmness of contact between the main contact members, and in order to insure a more definite and firm engagement between the main contact members and consequently improve the reliability 95 of operation of the regulator, the mechanism 100 22 is provided.

By referring to Fig. 2, it will be noted that the stem 21 is firmly secured to a link 26, secured to the horizontal arm of the lever 4, by means of a relatively stiff spring 27. 105 The spring 27 entirely relieves the lever 4 from all vibration that may be imparted thereto by the plunger 20. It does not, however, suppress the buzz inherent in alternating current regulators because of the light 110

tension that the spring 27 exerts upon a pin 28 that, in turn, is the attaching means for the connecting link 26. Therefore, two spring elements 29 are extended on opposite sides of the spring element 27 and connected to the stem 21 by means of laterally extending arms 30. The spring elements 29 are relatively light and serve to more firmly connect the stem 21 to the lever 4. I have found that by means of this structure no vibration is transmitted to the lever 4 and that the buzz is entirely eliminated. As a consequence, the main contact members 8 and 9 at all proper times firmly engage with each other.

The counter-weight 24 is suspended from the end of the lever 4 by means of the non-extensible element 25. If the counter-weight 24 were suspended by means of a spring, as has heretofore been the usual practice, the vibration imparted to the lever 4 would be very much increased instead of reduced since the mechanism 22 and a spring element for attaching the counter-weight 24 would form a mechanical structure that would tend to resonate.

While I have described, in detail, one embodiment of my invention, it will be understood that many modifications may be made therein without departing from the spirit and scope of the appended claims.

I claim as my invention:

1. An electrical regulator of the vibratory-contact type comprising a lever, a vibrating electromagnet having a plunger, a relatively heavy spring element, and a relatively light spring element located beside the heavy spring element and co-extensive therewith for connecting said plunger to the lever.
2. An electrical regulator comprising a lever, a movable contact member controlled thereby, a coöperating stationary contact member, a vibrating electromagnet, a plunger therefor, and spring elements of different sizes for attaching said plunger to said lever.
3. An electrical regulator comprising a lever, a movable contact member controlled thereby, a coöperating stationary contact member, an alternating current electromagnet, a plunger therefor, and means for secur-

ing said plunger to said lever for effecting engagement and disengagement between the said contact members, said means comprising heavy and relatively light spring elements for absorbing all vibrations imparted to said plunger whereby firm contact may be established between said contact members.

4. An electrical regulator comprising a lever, a contact member controlled thereby, a coöperating stationary contact member, an alternating current vibrating electromagnet, a plunger therefor, and heavy and relatively light spring elements for securing the plunger to the end of said lever.

5. An electrical regulator of the vibrating-contact type comprising a lever, an alternating current electromagnet, a plunger therefor, a relatively strong spring element for attaching said plunger adjacent to one end of said lever, and two relatively light spring elements disposed on opposite sides of said first spring element and co-extensive therewith.

6. An electrical regulator of the vibrating-contact type comprising a lever, an alternating current electromagnet, a plunger therefor, a relatively strong spring element for attaching said plunger adjacent to one end of said lever, two relatively light spring elements disposed on opposite sides of said first spring element and co-extensive therewith, and a counter-weight attached to the extremity of said lever adjacent to said spring elements.

7. An electrical regulator of the vibrating-contact type comprising a lever, an alternating current electromagnet, a plunger therefor, a relatively strong spring element for attaching said plunger adjacent to one end of said lever, two relatively light spring elements disposed on opposite sides of said first spring element and co-extensive therewith, and a counter-weight attached to the one extremity of said lever by means of a non-extensible member.

In testimony whereof, I have hereunto subscribed my name this 23d day of August, 1916.

ALLEN A. TIRRILL.
